UNITED STATES PATENT OFFICE

2,055,590

DEVICE FOR EXTINGUISHING FIRES ON
BOARD SHIPS

Rene Pugnet, St.-Nazaire, France, assignor of
one-half to Societe Anonyme des Chantiers et
Ateliers de Saint-Nazaire (Penhoet), Paris,
France, a corporation of France

Application August 8, 1935, Serial No. 35,366
In France March 13, 1935

1 Claim. (Cl. 299—73)

The invention relates to a fire extinguishing device for the extinction of fires starting in cabins on board vessels, the operation taking place directly above the fire and from a position protected from any smoke. This is accomplished by means of a fire extinguishing hydrant pipe passing through an orifice previously made in the ceiling.

In accordance with this idea, there is provided above the centre of each cabin, in the planking of the ship's deck above the cabin, an orifice through which may be passed a pipe having a nozzle at its lower end. A seating for a blank washer is provided in the wall surrounding said orifice, and this washer is adapted to be manipulated by means of a spanner wrench adapted to engage one or more blind holes provided in said washer. Opposite this orifice, and in the ceiling proper, there is cut a circular orifice of definite diameter covered by a plug forming an ornament for the ceiling of the cabin and held lightly in position by points, so as to be easily detached.

The annular wall surrounding the orifice in the ship's deck provides a spherical cup on which will rest, after the removal of the blocking plug, the special parti-spherical or swivel joint portion of a nozzle pipe of a fire extinguishing hydrant or supply pipe, said nozzle pipe terminating in a bent nozzle. The provision of this swivel joint makes it possible to direct the nozzle to all points necessary for the projection of the extinguishing liquid into all the corners of the cabin.

Between the hydrant or supply pipe and the extension carrying the nozzle, there is interposed a swivel joint constituted by a male part fixed on the hydrant pipe and suitably supported on a female part integral with the extension or nozzle pipe by means of a nut provided with two handles, so as to permit the nozzle to be turned in any direction whilst leaving the hydrant or supply pipe stationary. There is also hinged, below the orifice forming the seat for the swivel joint of the extension or nozzle pipe, a spring drawback flap automatically blocking the said orifice as soon as the nozzle is drawn out and thus facilitating the replacement of the blocking plug without having to fear the outlet of smoke.

The plug in the circular orifice of the ceiling proper is adapted to be removed by the insertion of the end of the nozzle through said orifice.

To clearly explain the invention it will be more particularly described with reference to

the annexed drawing, by way of example, in which:

Figure 1 is a vertical section showing the entire device;

Figure 2 is a detail showing the plug in position;

Figure 3 is a plan view of the spring flap.

Vertically above the centre of each cabin and in the planking of the upper deck 1 forming the ceiling, there is provided an orifice with two diameters 2, 3 in which there will be permanently fitted a part 4 of corresponding diameters and having a central orifice 6 forming a spherical cup 7, and a threaded part 8 in which there may be screwed a closing plug 9 covering the central orifice 6. The closing plug 9 is provided with one or more blind holes 10 (one being shown in the example) in which engage the male element or elements of a spanner wrench designed for the purpose.

The ceiling proper 11, of the cabin is provided with a circular orifice 12 of definite diameter located opposite the orifice 2, 3 and closed by a plug 13 adapted to form an ornamentation. This plug 13 is held lightly by points 14 so as to be easily disengaged and dropped into the cabin.

The closing plug 9 being removed, the mouthpiece or nozzle carrying pipe 16 of a hydrant or supply pipe 17, which comprises a swivel joint 18 adapted to be supported on the spherical cup 7 of the part 4.

The mouthpiece or nozzle pipe terminates in a nozzle 19 bent at right-angles and said nozzle, after having disengaged the plug 13 of the ceiling proper, passes through the orifice 12 and comes under the ceiling of the cabin.

Between the mouthpiece pipe 16 of the nozzle 19 and the supply pipe 17, there is interposed a swivel joint constituted by a male part 20 terminated by a hollow spherical part 21 fixed directly on the coupling member 22 of the supply pipe 17, and a female part 23 provided with handles 24.

The female part 23 is made integral with the mouthpiece pipe 16.

The male and female parts are held one against the other by a threaded nut 25 forming a cap for the stuffing box of the joint.

To the undersurface of the part 4, in which is made the orifice 6 forming at the same time the spherical cup 7 for the swivel joint 18, there is hinged at 26 a flap 27 subject to the action of a spring 28 tending to force it into its closing position. Packing 29 on said undersurface of the

part 4 ensures a tight joint, between the flap or door 27 and the part 4.

When the mouthpiece pipe 16 is drawn out of the opening 6 the spring 28 automatically causes the closing of the flap 27 which thus performs the part of a shutter.

In consequence of the swivel joint mounting of the mouthpiece pipe 16 of the nozzle it is possible to direct the nozzle to all points necessary for extinguishing the fire within the cabin whilst having a sufficiently tight joint to prevent passing of smoke from the cabin to the upper deck 4.

The form of the bent nozzle 19 at the end of the pipe 16 facilitates the directing of the jet under the ceiling.

Furthermore, the swivel joint interposed between the nozzle pipe 16 and the supply pipe 17 permits of rotating the nozzle 19 while leaving the supply pipe stationary.

Finally, the arrangement of the flap 27 under the orifice 6 of the part 4, automatically isolates the room or cabin as soon as the delivery of water is terminated and consequently when the nozzle pipe 16 is removed from the orifice 6, the flap 27 automatically moves to closed position, thereby preventing smoke and steam from being distributed over other portions of the ship.

The flap 27 in automatically covering the aperture 6, facilitates the putting into place of the plug 9 and permits of postponing this without inconvenience if more urgent work is to be carried out.

I claim:

A device for extinguishing a fire within a compartment having a wall, comprising a port in the wall forming a parti-spherical seat, a pipe adapted to extend through said port and having a nozzle at its outlet end arranged at an angle to the main portion of the pipe, a spherical member mounted on the pipe and movable with the latter for snugly engaging the seat when the pipe is inserted through the port, said member being free at all times to be moved away from the seat by the operator when the pipe is withdrawn from the port, a handle on the pipe and arranged to be used by the operator in manipulating the nozzle, said spherical member being positioned between the nozzle and the handle, a supply hose connected to the pipe for furnishing a fire extinguishing fluid to the pipe, a door arranged within the compartment, and means for automatically closing the door when the pipe is withdrawn from the port.

RENE PUGNET.
